UNITED STATES PATENT OFFICE.

WILLIAM F. ROTHE, OF EAST ST. LOUIS, ILLINOIS.

CARBURETER.

1,140,071.

Specification of Letters Patent.

Patented May 18, 1915.

Application filed May 1, 1912. Serial No. 694,392.

To all whom it may concern:

Be it known that I, WILLIAM F. ROTHE, a citizen of the United States, and a resident of the city of East St. Louis, in the county of St. Clair and State of Illinois, have invented a new and useful Improvement in Carbureters, of which the following is a specification.

This invention relates to carbureters and more particularly liquid fuel carbureters of the kind used in connection with internal combustion or explosion engines.

It has for its principal objects the production of a simple, efficient and easily adjusted device which gives a supply of liquid fuel proportionate to the inflow of air and controlled by the opening and closing of the throttle valve, and to attain certain other advantages hereinafter more fully appearing.

The invention consists in the parts and in the arrangements and combinations of parts hereinafter described and claimed.

In the accompanying drawings, which form part of this specification, and where like symbols refer to like parts wherever they occur, Figure 1 is a top plan view; Fig. 2 is a vertical section on the line 2—2 of Fig. 1; Fig. 3 is a vertical section on the line 3—3 of Fig. 1, an elbow pipe and screen being applied to one of the air intake openings and the other opening being closed by a cover plate; Fig. 4 is a horizontal section on the line 4—4 of Fig. 2; and Fig. 5 is a fragmentary perspective view of the reciprocating block which carries the needle-valve, and the cam, which co-operates therewith.

The carbureter shown in the drawings comprises a hollow shell 1. This shell 1 is provided with air intake openings 2 at opposite sides. In some cases both of these openings may be left open, but in cold weather one of the openings may be closed by a cover plate 3 and an elbow or other pipe connection 4 will be attached to the casing so as to communicate with the other opening. The elbow 4 will be connected to a pipe (not shown) leading from a place in proximity to the exhaust manifold or any portion of the engine which radiates heat sufficient to heat the pipe and thereby heat the air before it is taken into the carbureter. These arrangements are obvious. Therefore, they are not shown in the drawings. The openings 2 are preferably cov-

ered by screens 5 of relatively fine mesh so as to prevent back fires and keep sand and dirt out of the engine.

The openings 2 communicate with air chambers 6. These air chambers 6 are connected by a cross passageway 7 and they also communicate with a third air chamber 8 through openings 9. The cross passageway 7 communicates with a passageway 10 which is looped downward in an extension 21 of the bottom of the shell 1 and whose lower portion 11 constitutes the carbureting chamber. From the carbureting chamber 11 the passageway extends upward, as at 12, and it widens gradually toward its upper end and constitutes the mixing chamber.

The outlet opening 13 is controlled by a circular disk throttle-valve 14 mounted on a rock-shaft 15. This rock-shaft is provided at one end with an operating lever 16, and has a cam or eccentric 17 fixed on its opposite end. The cam 17 is arranged with respect to the valve 14 so that when said valve is in closed position the highest point of the cam is vertically below the rock-shaft. A liquid inlet or passageway 18 is provided in a nozzle member or plug 19 secured in a boss 20 at the bottom of the extension 21 in which the carbureting chamber 11 is located. The upper end of the nozzle member 19 is preferably made conical, as shown, so that the liquid may flow in all directions from the mouth of the passageway 18.

The passageway 18 is controlled by a needle-valve 22 which is slidably fitted in a vertical bore in the partition wall 23. The upper end portion of the needle-valve is screw-threaded, as at 24, and fitted in a screw-threaded bore in a reciprocating block 25, which works in a vertical bore provided in a boss 26 at the top of the shell 1. This block 25 is preferably cylindrical, as shown more clearly in Fig. 5, and has a portion cut away, as at 27, to provide a shoulder 28 adapted to bear against the cam 17 on the throttle-valve shaft 15.

A spring 29 is sleeved over the needle-valve 22 and is placed under compression between the top of the partition wall 23 and end of the block 25 so that it acts to hold the block with its shoulder 28 in contact with the cam 17 continuously. Hence, as the shaft 15 is rotated to open the throttle-valve and the high point of the cam 17 moves from under the shaft, the spring 29 raises the block 25 which in turn lifts the

needle-valve 22, thereby giving an increased supply of liquid in proportion to the increase of air that is drawn into the engine. By adjusting the needle-valve 22 in the block 25 the liquid inlet passage 18 may be entirely closed when the throttle-valve is closed, or it may be opened to any desired extent. In practice, however, the needle-valve is usually adjusted so that it is relieved slightly from the passageway 18 when the throttle-valve is closed.

In the upper part of the shell 1 is a chamber 30 which communicates with the mixing chamber 12 through the horizontal passageway 31. This chamber 30 also communicates with the air chamber 8 through an opening 32 which is normally closed by a lift-valve 33. This valve 33 is provided with a central tubular portion 34 which slides on a vertical rod 35 secured in the bottom of the casing 1. It is yieldingly held to its seat by a spring 36 which surrounds the rod 35 and bears against the under side of a tubular adjusting screw 37 fitted in a screw-threaded opening at the top of an upward extension 38 of the shell 1. The upper end of the rod 35 is screw-threaded, as at 39, and has an adjusting screw 40 working thereon and slidably fitted in the bore of the tubular adjusting screw 37. A spring 41 is sleeved over the rod 25 inside of the spring 36 and rests on the top of the valve 33. Normally, the adjusting screw 40 is set so that its lower end is a short distance above the upper end of the spring 41 so that the valve 33, in opening, moves initially against the tension of the spring 36. Then, as it moves higher, the spring 41 is brought into compression between the valve and lower end of the screw 40. By manipulating the screws 37 and 40 the tension of the springs 36 and 41 may be adjusted so as to control the movement of the valve 33 in order to prevent a too rich gaseous mixture under varying conditions.

The needle-valve 22 is provided with a manipulating knob or collar 42, and the screws 37 and 40 are provided with similar knobs or collars 43 and 44, respectively. These manipulating knobs or collars have knurled or corrugated peripheral faces so as to be engaged by retaining springs 45 which, as shown, are pieces of straight spring wire.

It is preferable to connect the two air chambers 6 by a passageway 6^a located between the outer wall of the shell 1 and wall of the mixing chamber 12 as shown more clearly in Figs. 2 and 4. In this way there is a continuous air space surrounding the carburetor proper, which is of obvious advantage in keeping the several chambers warm so as to make the liquid vaporize readily.

The liquid fuel may be supplied in any

suitable manner but, preferably, a reservoir comprising a shell 46 is secured to the underside of the carburetor; and a valve 47, controlled by a float 48, is provided so that the liquid is maintained at a constant level in said chamber 46. The liquid is admitted to the inlet passageway 18 by cross passages 49 provided in the plug 19, and a drain cock is provided on the plug.

In the operation of the carburetor, the engine being cranked or started and the throttle-valve open, a suction is created and the air is drawn into the shell 1 through the opening or openings 2. The air being drawn through the cross-passage 7 and down into the carbureting chamber 11 will take up the liquid that is drawn from the passageway 18 by the suction created, the vapor and air being commingled or mixed in the chamber 12. As the throttle-valve is opened to a greater extent, the spring 29 will lift the needle-valve 22 thus giving an increased supply of liquid and at the same time the increased suction will lift the valve 33 and a part of the air will pass from the chamber 8 or chambers 6 into the chamber 8 and through the opening 32, chamber 30 and passageway 31 to the mixing chamber 12 where it mixes with the air and vapor coming from the carbureting chamber 11.

Obviously, the device admits of considerable modification without departing from the invention. Therefore, I do not wish to be limited to the specific construction and arrangement shown.

What I claim is:

1. A carburetor comprising an outer shell and an inner shell spaced therefrom, said outer shell having an air intake opening therein, said inner shell having a horizontal passageway therethrough communicating at both ends with the space between said outer and inner shells, a downwardly looped passageway constituting a carbureting chamber, said last-mentioned passageway communicating at one end with said horizontal passageway, and at its opposite end with an upwardly flaring mixing chamber, said carbureting chamber having an oil inlet at the bottom thereof, an auxiliary air chamber communicating with said mixing chamber above said carbureting chamber and having an opening communicating with said air space between said outer and inner shells, a suction valve normally closing said opening, and a throttle-valve controlling the flow through said carburetor.

2. A carburetor comprising an outer shell and an inner shell spaced therefrom, said outer shell having an air intake opening therein, said inner shell having a horizontal passageway therethrough communicating at both ends with the space between said outer and inner shells, a downwardly looped passageway constituting a carbureting cham-

ber; said last-mentioned passageway communicating at one end with said horizontal passageway, and at its opposite end with an upwardly flaring mixing chamber, said carbureting chamber having an oil inlet at the bottom thereof, a valve for controlling said oil inlet, an auxiliary air chamber communicating with said mixing chamber above said carbureting chamber and having an opening communicating with said space between said outer and inner shells, a suction valve normally closing said opening, a throttle-valve controlling the flow through said carbureter, and means controlled by said throttle-valve for opening and closing said oil inlet valve simultaneously with and proportionately to the opening and closing of said throttle-valve.

3. A carbureter comprising an outer shell and an inner shell spaced therefrom, said outer shell having an air intake opening therein, said inner shell having a horizontal transverse passageway communicating at opposite ends with the space between said outer and inner shells, a passageway con-

stituting a carbureting chamber, said last-mentioned passageway communicating at one end with said horizontal transverse passageway, and at its opposite end with a mixing chamber, an auxiliary air chamber communicating with said mixing chamber beyond the first point of communication between said mixing chamber and said carbureting chamber, said auxiliary air chamber having an opening communicating with said air space between said outer and inner shells, said opening being normally closed by an upwardly opening suction valve, a spring acting continuously to seat said suction valve, an auxiliary spring for said suction valve, said auxiliary spring being inoperative while the suction valve is seated, and a throttle-valve for controlling the flow through said carbureter.

Signed at St. Louis, Missouri, this 27th day of April, 1912.

WILLIAM F. ROTHE.
